United States Patent Office

Des. 208,591
Patented Sept. 12, 1967

208,591

CONTAINER END

John S. Bozek, Chicago, Ill., assignor to Continental Can Company, Inc., New York, N.Y., a corporation of New York

Filed July 24, 1964, Ser. No. 81,001

Term of patent 14 years

(Cl. D58—26)

FIG. 1

FIG. 2

FIG. 3

The broken line showing of a portion of a can in FIGURE 1 is for illustrative purposes only.

I claim:

The ornamental design for a container end, as shown and described.
